Primary Examiner — Kendra Leslie Hamilton(74) *Attorney, Agent, or Firm* — Nelson Mullins Riley & Scarborough LLP(57) **CLAIM**

The ornamental design for an oral motor chew tool substantially as shown and described.

DESCRIPTION

FIG. 1 is a top, left, front perspective view of an oral motor chew tool, showing my new design;

FIG. 2 is a left side elevational view thereof;

FIG. 3 is a right side elevational view thereof;

FIG. 4 is a back side elevational view thereof;

FIG. 5 is a front side elevation view thereof;

FIG. 6 is a bottom side elevational view thereof; and,

FIG. 7 is a top side elevational view thereof.

The area inside the dashed lines in FIGS. 1 and 4-7 forms no part of the claimed design.

1 Claim, 4 Drawing Sheets(56)
